UNITED STATES PATENT OFFICE.

LEMUEL MCKINNON, OF OGDEN, UTAH, ASSIGNOR TO UNIVERSAL AIRLESS AUTO TIRE COMPANY, OF BUTTE, MONTANA, A CORPORATION OF MONTANA.

TIRE.

1,258,347.

Specification of Letters Patent.

Patented Mar. 5, 1918.

Application filed November 16, 1916, Serial No. 131,737. Renewed January 16, 1918. Serial No. 212,152.

To all whom it may concern:

Be it known that I, LEMUEL MCKINNON, a citizen of the United States, residing at Ogden, in the county of Weber and State 5 of Utah, have invented a new and useful Tire, of which the following is a specification.

The device forming the subject matter of this application is a tire, and the invention 10 aims to provide a resilient ring which, coacting with the tread portion of the tire casing, will afford the necessary resiliency, without rendering it necessary to inflate the casing or to use an inner tube.

Another object of the invention is to provide novel means for connecting the ends 15 of the spring ring.

It is within the province of the disclosure to improve generally and to enhance the 20 utility of devices of that type to which the present invention appertains.

With the above and other objects in view which will appear as the description proceeds, the invention resides in the combination 25 and arrangement of parts and in the details of construction hereinafter described and claimed, it being understood that changes in the precise embodiment of the invention herein disclosed can be made within 30 the scope of what is claimed, without departing from the spirit of the invention.

In the accompanying drawings:—

Figure 1 is a side elevation showing a rim and a casing, embodying the present invention, a portion of the elements above mentioned being broken away, so that parts appear in section;

Fig. 2 is a section on the line 2—2 of Fig. 1; and

Fig. 3 is a section on the line 3—3 of Fig. 2, parts being broken away; and

Fig. 4 is a perspective showing the washer.

In the drawings, the numeral 1 indicates a rim having clencher flanges 2 engaging 45 clencher beads 3 on a casing 4. The casing 4 may be assembled with the rim in any desired way, however. A retaining band 5 engages the edges of the casing 4 and holds the beads 3 interlocked with the flanges 2.

The band 5 is flexible, and it may be made 50 out of canvas or any other suitable material. A means is provided for drawing the ends of the band 5 together, so that it will exercise its office. This tightening means may 55 include a shaft 6 projecting through the

rim 1 and accessible from the under side of the rim. The tightening means has not been shown or described in detail, because it may be of any form adapted to the purpose. A suitable tightening means including such an element as the shaft 6 is shown in my Patent No. 1,176,073, granted on the 21st day of March, 1916.

A tread guard in the form of a ring 7 coacts with the outer portion of the casing 65 4. The tread guard 7 may be made of felt, leather, canvas or other suitable material, and has side flanges 8 which project toward the rim 1. Abutting against the inner surface of the tread guard 7 is a resilient ring 70 9 which preferably is made of metal. The guard 7 and its flanges 8 prevent the ring 9 from injuring the casing 4. The ends of the ring 9 are denoted by the reference characters 10 and 11, and are overlapped, as 75 shown in Fig. 1. The contacting inner faces of the ends 10 and 11 of the ring 9 may be beveled as shown at 12, if desired, thereby to reduce as much as possible, the space 21 between the end 10 and the guard 80 7 at the extremity of the end 11.

The end 10 of the ring 9 is provided with a slot 14 elongated circumferentially of the structure. The end 10 has teeth 15 which project into the slot 14 as shown in Fig. 3, 85 the teeth 15 being located along the longitudinal edges of the slot. A stud 16 is mounted in the end 11 and projects through the slot 14. Surrounding the stud 16 is a washer 17 which has opposed notches 18 90 adapted to coact with the teeth 15. The washer 17 includes a flange 19 bearing against the under face of the end 10 of the resilient ring 9. A nut 20 is threaded onto the inner end of the stud 16 and bears 95 against the flange 19 of the washer 17. The flange 19 overlaps the end 10 on each side of the slot 14, as indicated in Fig. 3.

In practical operation, the ends 10 and 11 of the ring 9 are moved apart in opposite 100 directions, until the desired stiffness in the ring 9 is obtained, the stud 16 moving circumferentially of the structure, in the slot 14, during this operation. The washer 17 is slipped over the stud 16, after the desired 105 adjustment has been obtained, the notches 18 in the washer receiving certain of the teeth 15. Relative movement between the ends 10 and 11 of the ring 9 will not then take place. The nut 20 is threaded onto the 110

end of the stud 16 and engages the flange 19 of the washer 17 to hold the washer in place, as shown in Fig. 1.

As hereinbefore indicated, the casing 4 is held on the rim 1 by tightening up the retaining band 5.

It is to be observed that the outer end 11 of the ring 9 covers the slot 14 in the end 10 of the ring, thereby to prevent the soft tread guard 7 from becoming embedded in the slot, and to permit the relative longitudinal movement between the ends 10 and 11 of the ring, when an adjustment of the ring is brought about.

Having thus described the invention, what is claimed is:—

In a device of the class described, a rim; a casing carried thereby; a soft tread guard bearing against the inner surface of the casing; a spring ring bearing against the inner surface of the soft tread guard and extended circumferentially of the casing, the ring including inner and outer overlapped ends, the inner end having a longitudinal slot provided at its sides with teeth, 25 the outer end covering the slot to prevent the soft tread guard from becoming embedded in the slot and to permit free relative longitudinal movement between the ends of the ring to secure an adjustment 30 thereof; a stud fixed to the outer end of the ring and projecting through the slot; a washer on the stud and located in the slot, the washer having oppositely disposed recesses receiving certain of the teeth on opposite sides of the slot and including a flange resting on the inner face of the inner end of the ring and extended beyond the sides of the slot; and a tightening element 35 on the inner end of the stud and engaging the flange.

In testimony that I claim the foregoing as my own, I have hereto affixed my signature in the presence of two witnesses.

LEMUEL MCKINNON.
